COMBINED ELECTRICALLY OPERATED DISH-WASHING UNIT AND KITCHEN ACCESSORY POWER SOURCE UNIT

Herbert Carvel Moore, Los Angeles, Calif., assignor to Electro-Way Corporation, Los Angeles, Calif., a corporation of California

Filed Jan. 22, 1962, Ser. No. 68,399

Term of patent 14 years

(Cl. D91—3)

FIGURE 1 is a perspective view of a combined electrically operated dishwashing unit and kitchen accessory power source unit showing my new design;

The rear and bottom are substantially plain except for the brush, hose and hooks as indicated in FIGURES 1, 3 and 4.

I claim:

The ornamental design for a combined electrically operated dishwashing unit and kitchen accessory power source unit, as shown and described.
